INVENTOR:

Geo. Gibbs

United States Patent Office.

GEORGE GIBBS, OF CANTON, OHIO.

Letters Patent No. 71,784, dated December 3, 1867.

IMPROVEMENT IN PLOUGHS.

The Schedule referred to in these Letters Patent and making part of the same.

Be it known that I, GEORGE GIBBS, of Canton, in the county of Stark, in the State of Ohio, have invented a new and useful Improvement in Ploughs; and I hereby declare that the following is a full and exact description thereof, reference being had to the accompanying drawings, and to the letters of reference marked thereon.

My invention consists, first, in employing a beam of wood entirely straight on the under side, and supported at the rear end by a detachable wooden brace, the lower end of which is connected to the standard by a socket; secondly, in forming the rear lower edge of the land-side like the front lower edge of a sleigh-runner; and thirdly, in flanging the nose of the coulter to one side, instead of the old method.

To enable others skilled in the art to make and use my invention, I will describe it by reference to the drawings.

The beam *a*, Figure 1, is straight on the under side, and fastened on the post in the usual manner. At *a* is a bored socket to receive one end of the round *b*; and at *c*, on the standard, is another, to receive the other end of said round or brace, forming the property of a triangular support to the plough. The rear and under side of the land-side *d* is formed like a sleigh-runner. The nose of the coulter *e*, Figure 2, is flanged to one side on the edge of the anvil, and is easily formed by this means.

The advantages of this construction are, first, a straight beam, in which the grain of the wood is parallel, is the strongest form, and, in connection with the brace *b*, secured in the manner shown in the drawing at *a* and *c* making it extremely strong and durable. It also retains the beam permanently in its original pitch. The sleigh-runner form of land-side renders the plough easier of control, both for tipping in or out of pitch while ploughing, as well as while sliding on the surface at the head-land. It also makes it easier of draught on the horses. The flanged coulter-nose is easily made, and has this advantage, in the fact that it can be edged to the extreme point of the coulter, which cannot be done by the old method. It possesses the property of angled metal, and insures that strength and thinness so requisite in a durable and easy-draught coulter.

I do not claim broadly the use of a brace at the hinder part of the plough, as it has been made and used in one form or another; but

What I claim as my invention, and desire to secure by Letters Patent, is—

1. The straight beam *a*, in combination with the detachable wooden brace *b* fitted into sockets, for the purpose as herein specified.
2. The land-side *d*, of the form and for the purposes as set forth.
3. The coulter-nose *e*, made and used as and for the purpose specified; and
4. The beam *a*, brace *b*, land-side *d*, and coulter-nose *e*, combined to form the design specified, when made and used as herein described.

GEO. GIBBS.
